CUTTING OFF MECHANISM FOR TUBE AND
BAG MAKING MACHINERYAdolph Potdevin, Garden City, Long Island, N. Y.,
assignor to Potdevin Machine Company, Brooklyn,
N. Y., a corporation of New York

Application March 30, 1934, Serial No. 718,153

3 Claims. (CL. 93—33)

This invention is directed to an improvement in cut off mechanism for tube and bag making machinery.

In certain types of cut off mechanism heretofore used in this type of apparatus it is customary to feed the material which is in the form of a tubular web along the upper and lower sides of a fixed plate. A stationary cut off member or knife is located above this plate and a striker bar is rotated upwardly from beneath the tube so as to sever the lower wall of the tube along the end of the fixed plate, the upper wall of the tube being severed along the edge of the knife. The knife is usually set slightly back of the end 15 of the fixed plate, so as to provide a flap on one wall of the tube.

Inasmuch as the fixed plate is necessarily of light material it has considerable spring to it with the result that in the cutting off operation it 20 is moved upwardly and strikes the edge of the knife dulling the same.

In handling paper, when making paper bags and tubes, the paper is relatively heavy so as to somewhat cushion the blow. In recent years 25 with the extensive use of glassine, "cellophane" and such materials which tear very readily this drawback has become very objectionable inasmuch as the cut off knife must be kept sharp for satisfactory results, and the present invention provides means for preventing raising of the fixed plate during the cutting off or severing operation so that contact of the plate with the edge of the knife is avoided.

In the accompanying drawing:

35 Fig. 1 is a sectional side elevational view of an embodiment of my invention;

Fig. 2 is a view similar to Fig. 1 showing the cutting off mechanism in operation; and

Fig. 3 is a plan view.

40 Referring to the drawing in detail, 1 and 2 designate the feed rollers by which the tubular web 3 is advanced through the machine to the cutting off mechanism. During the cutting off operation the tube is retarded in its advance by 45 pinch rolls 4 and 5 running at a lower peripheral speed than the feed rollers to create slack in the material during this period. This slack is controlled during the cutting off operation by rollers 6 and 7 located intermediate the cut off 50 station and the pinch rolls. This mechanism, however, constitutes the subject matter of my pending application Serial No. 585,520, filed January 8, 1932, and will not be referred to in detail herein.

55 The cutting off mechanism comprises a fixed

plate 8 in the path of the tubular material, this material passing above and below the plate and shown in the drawing. This plate is of thin light metal.

Above the fixed plate 8 and disposed slightly to the rear of the end of the plate, depending upon the length of the wall flap desired, is a fixed knife 9 mounted on a suitable bracket 10. Co-operating with the plate 8 and knife 9 is a striker bar 11. This bar is shown as mounted on a 10 driven shaft 12 disposed parallel to the travel of the tubular material 3 so that the bar is rotated upwardly from beneath the advancing material to intersect the material. This method of mounting and driving the striker bar may be varied as 15 will be appreciated within the spirit and scope of my invention.

Just above the plate 8 is a stop plate 12 mounted on bracket 13. This stop plate is spaced above the fixed plate 8 sufficiently to permit the wall 20 of the tubular material 3 to pass therebetween.

With this mechanism in operation the material 3 is continuously advanced, and at a predetermined instant the striker bar 11 is moved upwardly as shown by a comparison of Figs. 1 25 and 2, carrying the material 3 upwardly to sever the lower wall thereof across the end of the fixed plate 8 and the upper wall against the edge of the knife 9. During the severing of the lower wall it will be appreciated tension is exerted in an upward direction on the plate 8, and while this plate is of springy material, light metal, it is positively prevented from contacting with the knife 9 to dull the same, by the stop 30 plate 12.

35 It will be seen, therefore, that my invention provides an arrangement particularly useful in working with glassine, "cellophane" and similar materials in that the knife 9 which is provided for cutting through one wall of the tube material 40 is kept out of contact with the plate 8 and dulling of the knife prevented.

What I claim is:—

1. Cut-off mechanism for bag and tube making machines comprising in combination a relatively thin fixed plate in the path of the tubular material being handled and disposed so as to telescoped thereby, a movable member out of the plane of one face of said plate, a fixed knife out of the plane of the other face of the fixed plate, 45 said movable member being movable in a direction to divide one wall of the tube across the end of the fixed plate and the opposite wall of the tube across the edge of the said knife, and 50 means intermediate the said fixed plate and fixed 55

knife for maintaining the edge of said knife and the face of the plate out of contact with each other at all times.

2. Cut-off mechanism for bag and tube making machines comprising in combination a relatively thin fixed plate in the path of the tubular material being handled and disposed so as to be telescoped thereby, a movable member out of the plane of one face of said fixed plate, a fixed knife out of the plane of the other face of the fixed plate, said movable member being movable in a direction to divide one wall of the tube across the end of the fixed plate and the opposite wall across the edge of the said knife, and means disposed at the knife side of the fixed plate intermediate it and said knife and spaced from the fixed plate sufficiently to permit the tubular material to pass between it and the fixed plate, for maintaining the knife and fixed plate out of contact with each other at all times.

3. Cut-off mechanism for bag and tube making machines comprising in combination a relatively thin fixed metal plate in the path of the tubular material being handled, said plate being so disposed as to be telescoped by the material, 5 a striker bar adapted to engage one wall of the tubular material as the same leaves the fixed plate to sever or divide said wall across the end of the fixed plate, a fixed knife disposed out of the plane of one face of the fixed plate and in 10 such position that the undivided wall of the tubular material on continued movement of the striker bar is moved into engagement with the edge of said knife to sever or divide the remaining wall of the tubular material, and a stop 15 member interposed between said knife and said fixed plate maintaining the fixed plate and knife out of contact with each other at all times.

ADOLPH POTDEVIN. 20
